UNITED STATES PATENT OFFICE.

HUGH W. SANFORD, OF KNOXVILLE, TENNESSEE.

RAILWAY CAR.

Application filed September 25, 1923. Serial No. 664,652.

To all whom it may concern:

Be it known that I, HUGH W. SANFORD, a citizen of the United States, residing at Knoxville, in the county of Knox and State of Tennessee, have invented a new and useful Improvement in Railway Cars, of which the following is a specification, reference being had to the accompanying drawing.

This invention relates generally to railway cars and particularly to the trucks of mine cars. The improvement includes features of the truck frame, axles, axle boxes or bearings in mine cars in which a part or all of the wheels are fixed on the axles and the axles rest in bearings which are supported by the car body and which bearings are associated with pedestals.

The object of this invention is to provide a structure embodying a satisfactory truck frame and axle boxes and axles and pedestals and wheels so associated as to render the axle boxes free from wheel end thrust, the pedestals, taking said thrust and transmitting it to the car floor or car body and not to the axle boxes, the axle boxes thus being free or "floating" and fully adapted to keep in alignment with the axles and maintain a balanced engagement with the axles.

Efforts have heretofore been made to produce self-aligning axle boxes; but on account of receiving end thrust from the wheel, the axle box has not been free to maintain its parallel relation with the axle and to bear in a balanced way upon the axle.

As has heretofore been done in attempts to produce a self-aligning axle box, in any construction the engagement with the axle box for the support of the car body is on the upper part of the axle box midway between its ends.

A further object of the invention is to combine with the free axle box suitable means for delivering lubricant into the axle box, such means being associated with the truck frame and axle box as to be free for movement with the axle box and at the same time be suitably protected by the truck frame.

The parts of the frame which thus protect the lubricating means also serve to hold the pedestals for maintaining the axles parallel to each other and to space the pedestals and the parts to which the pedestals are directly secured from each other at the

proper distances, whereby a finished truck is formed ready to receive a car body made at the factory where the truck is made or at some other place to which the truck is shipped by the truck manufacturer.

In the accompanying drawings,

Fig. 1 is a plan of a truck embodying my improvement;

Fig. 2 is an upright section on the line, 65 2-2, of Fig. 1, looking toward the right;

Fig. 3 is a perspective of one end of one of the longitudinal truck members, said part being shown inverted;

Fig. 4 is an upright section on the line, 70 4-4, of Fig. 1, looking toward the left;

Fig. 5 is an upright section on the line, 5-5, of Fig. 4, looking toward the left;

Fig. 6 is an upright section on the line, 75 6-7-6-7, of Fig. 4, looking toward the right;

Fig. 7 is an upright section on the line, 6-7-6-7, of Fig. 1, looking toward the left;

Fig. 8 is an upright section on the line, 80 8-8, of Fig. 4, looking toward the left;

Fig. 9 is an upright section on the line, 9-9, of Fig. 4, looking toward the left;

Fig. 10 is an upright section on the line, 10-10, of Fig. 4, looking toward the right; 85

Fig. 11 is an upright section on the line, 11-11, of Fig. 4, looking toward the right;

Fig. 12 is a horizontal section on the line, 12-12, of Fig. 5;

Fig. 13 is a perspective of the pedestal; 90

Fig. 14 is a horizontal section on the line, 14-14, of Fig. 4.

Referring to said drawings, A, (A) are axles, G, G are wheels having hubs, G¹, surrounding the axles. The axles extend 95 through the pedestals, C. B¹, B² are two cross plates. Each of these plates is slotted or cut out at each end to leave two arms, B⁴, in which are holes, B⁵, and which arms have outer downward-directed marginal 100 flanges, B⁶. The space between these arms is made right to bring one of the arms close to each side of the recess, B¹, in the floor, B, and the sides of the pedestals, C, and to bring the edge of the plate which is between the arms close to the pedestal. Between the plates, B³, are two connecting members, I, each having its ends rigidly joined to the adjacent flanges, B⁶, of the plates, B³. In the form shown in the 110 drawings, each of said members is angle-form in cross section and has one of its

flanges, I¹, directed downward and placed toward the wheels, G. The upper flange of each member, I, is cut just long enough to adapt its ends to bear against the adjacent floor, B⁶, of the adjacent cross plate, while the flange, I¹, is left long enough to be bent horizontally and at right angles to the length of the member, I, so as to form a tongue, I², extending across the lower face 10 of the upper flange and lying flatwise against the adjacent flange, B⁶, and be secured thereto by rivets, I⁴. The two cross members, B³, and the connecting members, I, form a rectangular frame which becomes 15 a part of the truck of the car. Near each wheel each of said flanges, I¹, is provided with an orifice, I³, large enough to receive a lubricating pipe hereinafter described.

A pedestal, C, is attached to each end of 20 each cross plate, B³. The cross plates being definitely spaced from each other by the connecting members, I, the pedestals are held in definite relation to each other, the pedestals on one plate, B³, being on the same 25 axial line, and the axial line of the pedestals on one plate being held parallel to the axial line of the pedestals on the other plate.

The part of each axle which extends through the wheel and through the axle 30 bearing or bearing box is cylindrical and of uniform diameter. The entire axle is preferably of this form, in order that it may be made of cold drawn steel, a process which is economical and also affords steel of high 35 quality, whereby an axle of a given diameter is made stronger than can be made of hot rolled commercial steel.

B is the floor of the car body. In the 40 form shown by the drawings, this floor is of wood. Its lower face is recessed at B¹ to make room for the pedestal or housing, C, of the axle bearing or axle box body, D. The upper part of said pedestal has a horizontal face, C¹, resting against the wood 45 floor, as shown by Figs. 4, 5, 8, and 9. On the floor above the recess, B¹, is a metal washer plate, B², through which extend four bolts, as will appear further on.

On each side of the pedestal are two lugs, 50 C², which bear upward and sidewise against the adjacent arms, B⁴. Bolts, B⁷, extend downward through the washer plate, B², the floor, B, the adjacent arm, B⁴, and the adjacent lug, C², and bind said parts to each 55 other. The drawings show four such bolts applied to the pedestal.

The outer part of the side wall of the 60 pedestal, C, extends entirely around the axle body, D; but the inner part of said side wall reaches downward only as far as the horizontal, middle plane of the axle. The inner end of the pedestal, C, has an 65 upright wall, C³, which extends downward to the middle, horizontal plane of the axle and is cut out sufficiently to receive the axle

and the adjacent end of the axle body, D. C⁴ is the outer end wall of the pedestal. This has an oblong orifice, C⁶, which permits up and down movement of the pedestal and the adjacent part of the car body relative to the adjacent part of the axle. On the outer end wall, C⁴, is the annular outward-directed flange, C⁵, surrounding the axle. Said flange is approximately concentric to the axle and extends outward over the washers, H, and around the adjacent end of the hub, G¹, the washers, H, intervening the end of the hub and the outer pedestal wall, C⁴. The diameter of the flange, C⁵, is sufficient to leave a space between said flange on the one hand and the washers and the adjacent outer face of the hub, on the other hand, to receive packing to prevent passing of dust and cinders and to hold grease or other lubricant.

Between its ends, the upper face of the body, D, of the axle bearing has a transverse horizontal ridge or summit, D¹, resting against the lower face of the upper wall of the pedestal, C. Said ridge or summit is transverse to the axle and forms a line on which the axle box body may relatively rock on the lower face of the upper wall of the pedestal, this feature contributing to making this a self-aligning axle box, such as is already known in this art. The rocking above mentioned is on a horizontal face. Provision is also made for rocking on upright faces against the side walls of the pedestal. For this purpose upright, curved contact faces, D⁹, are put on the outer faces of the axle box body, said faces, D⁹, being concentric to an upright line cutting the axis of the axle approximately midway between the ends of the axle box body. Thus provision is made for a rocking which is equivalent to a partial rolling of the axle box on the upright pedestal wall against which the axle box is at the time pressing. Theoretically, the horizontal diameter of the axle box through the upright axis to which the faces, D⁹, are concentric should be slightly less than the space between the adjacent upright walls of the pedestal, in order that the side of the axle box body which is not pressing against the upright pedestal wall adjacent thereto shall be free from said wall and not tend to hinder the rocking movement on the opposite pedestal wall.

The inner or right-hand end of the bearing body has an upright wall, D², which fits closely around the axle but permits free turning of the axle in the bearing. Within said end, a channel, D⁸, is formed in the face of the wall which is next the axle. This channel is to receive felt or other packing material adapted to prevent the passing of oil and dust or cinders.

The opposite or outer end of the bearing

or box body has no end wall formed integral with said body. A ring, D⁵, surrounds the axle and bears against the end of said body. The main part of said ring is in a plane transverse to the axle. Next to the axle said ring has a flange, D⁶, directed toward the opposite end of the bearing. Said ring also has an outer flange, D⁷, which extends over a part of the outer face of the bearing body. Parts, D⁸, of said flange are bent into a circumferential channel, D⁴, formed on the outer face of the bearing body. By this means, said ring is removably secured to the bearing body.

15 In the space around the axle and within the bearing body are anti-friction rollers, E, placed parallel to the axle and having at each end a small journal, E¹. At the outer end of the bearing, the flange, D⁶, of the ring, D⁵, prevents the rollers, E, from moving out of position by movement toward the axis of the bearing, when the bearing is removed from the axle. At the opposite or inner end of the bearing, a retaining ring, 20 E², surrounds the axle and extends between the axle and the adjacent journals, E¹, said ring being so proportioned as to preclude movement of the journals, E¹, toward the bearing axis for the dislodging of the rollers when the bearing has been removed from the axle.

25 The outer end of the hub, G¹, has two diametrically opposite notches, G², which are adapted to be brought into alignment with the transverse axle aperture, A², for receiving a cotter pin, G³, which will serve to prevent rotation of the wheel independently of the axle. Next to the outer end of the hub, a sleeve, A¹, surrounds the axle and is secured thereto by a transverse cotter, A³. This sleeve, A¹, bears against the adjacent end of the hub.

30 It will now be seen that wheel thrust parallel to the axle and toward the car body will be taken by the thrust wall, C⁴, and transmitted by the latter to the pedestal. The pedestal resists such thrust because of the binding by the bolts, B¹, and abutting of the pedestal against the edge of the cross plate, B³, between the arms, B⁴, and against the upright face of the wood floor, B, above said edge of the cross plate. Thus said end thrust is transmitted to the car floor or body.

35 Thus the axle box is left free or "floating" on the axle within the pedestal and is entirely free to take the rocking movements above described and to move endwise on the axle to the extent permitted by the fixed end walls 40 of the pedestal, the space between said walls being intentionally made a little longer than the length of the axle box. This structure makes the axle box actually self-aligning—freely self-aligning. An axle box which receives wheel thrust is not free for self-align-

ing and can not bear evenly on the axle. Parts of the bearing surfaces will be pressed or jammed excessively on the axle, whereby free turning of the axle is prevented and damaging strains are concentrated upon portions of the bearing.

45 While the drawings show the axle box provided with anti-friction rollers, it is to be understood that the interior of the axle box may be formed otherwise, as with brass or cast iron bearing plates or faces. In such case, the axle box is still free or "floating" and self-aligning.

50 Adjacent each wheel, G, a pipe F, for carrying lubricant extends loosely through the orifice, I², of the adjacent member, I, toward the opposite connecting member, I, until the middle transverse upright plane of the axle box is reached and then turns toward the axle box and through a relatively large 55 notch, C⁷, in the adjacent wall of the pedestal and thence into the adjacent wall of the axle box, said pipe being threaded or otherwise well secured in said wall of the axle box. On the outer end of said pipe, F, is any 60 suitable device adapted for receiving and transmitting lubricant into said pipe. This may be a nipple or screw plug, F¹, of well-known form for connection with a grease gun. The orifice, I², and the notch, C⁷, are 65 to be large enough to allow the pipe, F, to move to any extent demanded by the rocking or other shifting of the free or "floating" axle box. The orifice, I², is to be far enough 70 away from the adjacent axle to bring the outer end of the pipe, F, out of the range of the adjacent wheel, G, in order that lubricant may be injected into the axle box without passing between spokes or any other 75 opening in the wheel and without the necessity of turning the wheel into any particular position on the axle. This provision will be 80 a matter of much convenience in the operation of such cars. At any time when the car is stationary, lubricant may quickly be 85 injected into the four axle boxes without regard to the positions of the wheels on the axles.

85 It will now be observed that the axles and the wheels and the axle boxes and the pedestals and the cross plates and the connecting members together form a truck which is 90 ready to receive the car body, and that such trucks may be made in quantity independently of the bodies and may receive the bodies at the factory where the trucks are 95 made or may receive the bodies at some distant place.

95 In my Patent, No. 1,477,449, dated Dec. 11, 1923, the outer end wall, C⁴, of the pedestal of this application is omitted and in place thereof a thrust wall is detachably secured to the open end of the pedestal; and in said application claims are directed to 100 combinations including the pedestal and the 105

thrust wall detachably secured to and supported by the adjacent end of the pedestal.

While the drawings illustrate a structure in which the axle boxes are between the wheels, it is to be understood that my invention is equally applicable when the wheels are placed between the axle boxes, these two forms being well-known in this art as interchangeable equivalents.

10. I claim as my invention,

1. In a railway car, the combination of cross plates, connecting members joining the cross plates, pedestals applied to the cross plates, axle boxes applied to the pedestals, lubricant delivering pipes extending through the connecting members and into the axle boxes, axles extending through the axle boxes, and wheels on the axles, substantially as described.

20. 2. In a railway car, the combination of cross plates having arms, connecting members joining the cross plates, pedestals applied to the cross plates and extending between said arms, axle boxes applied to the pedestals, lubricant delivering pipes extending through the connecting members and into the axle boxes, axles extending through the axle boxes, and wheels on the axles, substantially as described.

25. 25. 3. In a railway car, the combination of cross plates, connecting members having flanges folded to form tongues lying against and secured to the cross members, pedestals applied to the cross plates, axle boxes applied to the pedestals, axles extending through the axle boxes, and wheels on the axles, substantially as described.

30. 30. 3. In a railway car, the combination of cross plates, connecting members having flanges folded to form tongues lying against and secured to the cross members, pedestals applied to the cross plates, axle boxes applied to the pedestals, axles extending through the axle boxes, and wheels on the axles, substantially as described.

40. 4. In a railway car, the combination of cross plates, connecting members joining the cross plates and having orifices, pedestals applied to the cross plates, axle boxes applied to the pedestals, lubricant delivery pipes extending through said connecting member orifices and into the axle boxes,

45. axles extending through the axle boxes, and wheels on the axles, substantially as described.

50. 5. In a railway car, the combination of a pedestal, wheels, an axle, an axle box adapted to rock in the pedestal, and a lubricant conveying pipe leading into the side of the axle box and rigidly secured to said box, substantially as described.

55. 6. In a railway car, the combination of a pedestal, wheels, an axle, an axle box adapted to rock in the pedestal, a lubricant conveying pipe leading into the side of the axle box and rigidly secured to said box, and means loosely surrounding said pipe, substantially as described.

60. 7. In a railway car, the combination of an axle, a wheel on the axle, an axle box surrounding the axle, means on the car bottom making engagement with the upper face of the axle box and said means extending

between the hub and the axle box and free from the end of said box to receive wheel end thrust and transmit said thrust to the car bottom independently of the axle box, whereby the axle box is independent of end thrust and is free or floating on the axle, substantially as described.

8. In a railway car, the combination of an axle, a wheel on the axle, an axle box surrounding the axle, a pedestal resting on the axle box and secured to the car bottom and in operative relation with the wheel to receive wheel end thrust and transmit said thrust to the car bottom independently of the axle box, the axle box being independent of end thrust and free or floating on the axle, substantially as described.

9. In a railway car, the combination of an axle, a wheel on the axle, an axle box surrounding the axle, a pedestal resting on the axle box and secured to the car bottom and having an end wall free from the axle box and positioned to receive wheel end thrust and transmit said thrust to the car bottom independently of the axle box, the axle box being independent of end thrust and free or floating on the axle, substantially as described.

10. 10. In a railway car, the combination of an axle, a wheel on the axle, an axle box surrounding the axle, a pedestal resting on the axle box and secured to the car bottom and having an end wall surrounding the axle and free from the axle box and positioned to receive wheel end thrust and transmit said thrust to the car bottom independently of the axle box, the axle box being independent of end thrust and free or floating on the axle, substantially as described.

11. 11. In a railway car, the combination of an axle, a wheel on the axle, an axle box surrounding the axle, a pedestal resting on the axle box and secured to the car bottom and having an end wall extending over each end of the axle box free from said box, one of said end walls being positioned to receive wheel end thrust and transmit said thrust to the car bottom independently of the axle box, the axle box being independent of end thrust and free or floating on the axle, substantially as described.

12. 12. In a railway car, the combination of an axle, a wheel on the axle, an axle box surrounding the axle, a pedestal making rocking engagement with the axle box approximately midway between the ends of said box and secured to the car bottom and in operative relation with the wheel to receive wheel end thrust and transmit said thrust to the car bottom independently of the axle box, the axle box being independent of end thrust and free or floating on the axle, substantially as described.

13. 13. In a railway car, the combination of an axle, a wheel on the axle, an axle box

surrounding the axle, a pedestal making 5
rocking engagement with the axle box approximately midway between the ends of said box and secured to the car bottom and
having an end wall free from the axle box and positioned to receive wheel end thrust and transmit said thrust to the car bottom independently of the axle box, the axle box being independent of end thrust and free 10 or floating on the axle, substantially as described.

14. In a railway car, the combination of an axle, a wheel on the axle, an axle box 15 surrounding the axle, a pedestal making rocking engagement with the axle box approximately midway between the ends of said box and secured to the car bottom and having an end wall surrounding the axle and free from the axle box and positioned 20 to receive wheel end thrust and transmit said thrust to the car bottom independently of the axle box, the axle box being independent of end thrust and free or floating on the axle, substantially as described.

25 15. In a railway car, the combination of an axle, a wheel on the axle, an axle box surrounding the axle, a pedestal resting on the axle box and adapted to make rocking

side engagement with the axle box approximately midway between the ends of said box 30 and said pedestal being secured to the car bottom and free from the axle box ends and in operative relation with the wheel to receive wheel end thrust and transmit said thrust to the car bottom independently of the axle box, the axle box being independent of end thrust and free or floating on the axle, substantially as described.

16. In a railway car, the combination of an axle, a wheel on the axle, an axle box 40 surrounding the axle, a pedestal resting on the axle box and secured to the car bottom and having an end wall integral with the body of the pedestal and free from the axle box and positioned to receive wheel end 45 thrust and transmit said thrust to the car bottom independently of the axle box, the axle box being independent of end thrust and free or floating on the axle, substantially as described.

In testimony whereof I have signed my name, this 18th day of September, in the year one thousand nine hundred and twenty-three.

HUGH W. SANFORD.
